OSCILLATORY CIRCUITS

Application filed April 10, 1925, Serial No. 22,026, and in Germany April 25, 1924.

My invention relates to high frequency signalling systems and more particularly to a new and useful inductance coil and system for using said coil.

5 An object of the invention is to provide a coil of the above kind whose inductance will vary with the value of the current flowing thru the winding thereof and which will have low hysteresis and eddy current losses.

10 Another object is to provide method and means for using the coil which will be efficient in operation.

Other objects will be apparent from the following description and claims when considered with the accompanying drawing.

The use of coils provided with iron cores in high frequency systems is known. For the purpose of reducing iron losses, it is well known to make the cores of subdivided 20 iron. It has been shown that with cores consisting of iron wires a special effect obtains, for, in the presence of such extremely fine transverse subdivision without interruption of the flux path in the direction of the 25 flux the magnetization is large, while the eddy-current losses become very low. The use of such coils is known for the purposes of high frequency transmitters employing frequency transformers.

30 The inductance of such coils, at a given strength of current, undergoes very considerable changes, since the permeability at a certain strength of current experiences a very sudden rise. Now, the present invention utilizes this effect of strong rise in permeability when such thin wires are used, in such a manner that coils provided with cores of iron wires are employed for receiving purposes, the wire having a diameter smaller

40 than $\frac{1}{16}$ of one millimeter and made from ferro-nickel alloys. The best alloy known to me at the present time for this purpose is the so-called "permalloy" containing about 80 percent nickel and 20 percent iron.

45 For instance, a coil equipped with an iron core of the kind described can be used as an inductance coil contained in an oscillation circuit, with the saturation of the coil being so chosen that for the strength of the incoming current the inductance of the coil

just corresponds to the resonance condition. Upon the arising of stronger disturbances and oscillations, the permeability changes considerably and therefore also the inductance, with the consequence that marked detuning of the circuit is produced. In this manner, as can be seen, a sort of amplitude selection is attainable.

55 In the various figures of the drawing I have shown a preferred form of my invention.

Fig. 1 shows the circuit arrangement.

Figs. 2 and 3 show modified forms of the wire core wherein Fig. 2 shows a closed ring form and

65 Fig. 3 shows an open ring with a constant air gap.

Referring to Fig. 1 of the drawing, I is the usual antenna circuit and II is a tuned circuit coupled to antenna circuit I by means of coupling coils 1 and 2. The iron core inductance is denoted by A and is made up of wires 3 of very small diameter, preferably less than one tenth of one millimeter and a winding 4. The material from which 70 the wires are made is, according to the invention, an alloy consisting of about 80 percent nickel and 20 percent iron. The tuned circuit II has coupling coil 2, inductance A, 75 the signal responsive means and a tuning 80 condenser 5 all in series.

It will easily be seen that if the circuit II is tuned to resonance at a certain frequency, the exact amount of current must flow thru circuit II to give the coil A its 85 proper inductance.

The arrangements shown in Figs. 2 and 3 are modified forms which the wire cores shown in Fig. 1 may assume.

90 The use of coils of the kind described is convenient also for the purposes of coupling various parts of the receiving apparatus. Coils of the same sort could also be used in reception for frequency raising, and also for frequency reduction. It is thus feasible to 95 change the incoming high frequency waves into low frequency by multiple reduction of frequency.

Having described my invention, I claim:

1. An oscillatory circuit resonant to a de- 100

sired signal of a predetermined current strength adapted to be used with a signal responsive means, including a tuning condenser and an inductance device connected therewith, said inductance device having a ferro-nickel core so constructed as to reduce eddy current losses to a low value and being adapted to bring said circuit to a non-resonant condition upon an increase of current strength beyond that of said predetermined strength.

2. An oscillatory circuit resonant to a desired signal of a predetermined current strength including a tuning condenser and an inductance device connected in series therewith, said device having a core composed of permalloy wires for bringing said circuit to a non-resonant condition upon an increase of current strength beyond said predetermined strength.

3. An oscillatory circuit comprising means to tune it to a desired signal of a predetermined current strength, and an inductive means including a magnetic, metallic core for bringing said circuit to a non-resonant condition upon an increase of current strength beyond said predetermined strength, said core being so constructed as to maintain eddy current losses at a low value.

4. An oscillatory circuit resonant to a desired signal of a predetermined current strength adapted to be used with a signal responsive means, including a tuning condenser, an inductance device connected thereto, said device having a permalloy core for bringing the circuit to a non-resonant condition upon an increase of current strength beyond that of said predetermined strength, said core being constructed to maintain eddy current losses at a low value.

ALEXANDER MEISSNER.
